UNITED STATES PATENT OFFICE.

CHARLES O. C. LINDROOTH, OF REDFIELD, SOUTH DAKOTA, ASSIGNOR TO THE PHARIS
TIRE & RUBBER COMPANY, OF NEWARK, OHIO, A CORPORATION OF OHIO.

DESIGN FOR A RUBBER TIRE.

48,906.

Specification for Design.

Patented Apr. 18, 1916.

Application filed October 28, 1915. Serial No. 58,497. Term of patent 14 years.

To all whom it may concern:

Be it known that I, CHARLES O. C. LINDROOTH, a citizen of the United States, residing at Redfield, Spink county, South Dakota, have invented a new, original, and ornamental Design for Rubber Tires, of which the following is a specification, reference being had to the accompanying drawing, forming part thereof, in which—

Figure 1 is a plan view of a portion of

the tread face of the tire, and, Fig. 2 is a transverse section of my newly designed tire taken on line 2—2 of Fig. 1.

I claim:

The ornamental design for a rubber tire, as shown.

CHARLES O. C. LINDROOTH.

Witnesses:

CHARLES L. F. CARY,
EDITH SMITH.
